(57) CLAIM

The ornamental design for a disposable seat cover for rental bikes and exercise equipment, as shown and described.

DESCRIPTION

FIG. 1 is a top isometric view of a disposable seat cover for rental bikes and exercise equipment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an isometric view thereof in a deployed configuration.

The broken lines depicting lettering in FIGS. 1-6 and 8 form no part of the claim. The broken lines depicting equipment structure in FIG. 8 form no part of the claim.
